UNITED STATES PATENT OFFICE

CLARENCE E. WISE, OF PITTSBURGH, PENNSYLVANIA, ASSIGNOR TO CRUCIBLE STEEL COMPANY OF AMERICA, A CORPORATION OF NEW JERSEY

PLOWSHARE

Application filed October 9, 1929. Serial No. 398,277.

Heretofore plowshares have commonly been made of so-called soft-center steel, meaning essentially a laminated composite steel plate comprising an inner layer of low-carbon steel which is soft and tough, having formed or welded upon each of its opposite faces an outer layer of steel of higher carbon content which is hardened. In such prior soft-center plowshares the inner low-carbon steel layer has extended throughout the length of the share, leaving the said inner layer exposed along the edge of the nose and at the nose-point, although in some cases thin pieces or "shins" of hard steel have been welded above and below, and sometimes on opposite sides of, the nose of the share. In all such cases the hardened steel outer layers (one or both) at the nose, and particularly at and near the point of the nose, wear away more or less rapidly, thus exposing the inner soft layer directly to scouring by stones in the ground, and then the plowshare is soon worn out.

It is the object of the present invention to improve the plowshare in these respects, and thus to provide one having a materially longer effective life, while not impairing the strength of the share as a whole, and to that end I form the nose also of the share entirely of high-carbon steel, which is sharpened at the point and hardened in the usual manner.

In the accompanying drawings Figure 1 is a perspective view of a composite steel plate; Figure 2 is a perspective view of a blank which has been sheared from a plate such as that shown in Figure 1; Figure 3 is a perspective view of a plowshare embodying the invention, which has been formed from the blank shown in Figure 2; and Figure 4 is a view in cross-section taken on the line IV-IV of Figure 3. It will be understood that Figures 1 and 2 are only illustrative, and that no attempt at accurate scaling has been made.

The composite steel plate 1 of Figure 1 has been rolled down from a composite ingot having a low-carbon core and a surrounding envelope of higher carbon steel, as is a well-known practice, the low-carbon central layer

being indicated by the numeral 2, and the high-carbon envelope by the numeral 3. Heretofore in the manufacture of a plowshare from a composite steel plate such as is shown in Figure 1, it has been the practice to shear off, along the dotted lines 4, 4, the opposite solid high-carbon edge portions 5, 5 of the composite plate, thus leaving the opposite edges of the inner low-carbon layer 2 exposed, and then cut the blank for the plowshare from the sheared plate. In the manufacture of my improved plowshare by the procedure now being described I do not shear away the high-carbon edges 5, 5, but I leave the composite plate 1 intact at its edges, and I cut out of it (as shown by the shaded portions and by the dotted lines 6) the blank 7, one of which is shown in Figure 2, with the edges of the low-carbon inner layer 2 exposed upon three sides, and its end taken from the solid high-carbon edge portion 5 of the composite plate 1. The blank 7 is then forged in the usual way to form the plowshare 8 shown in Figures 3 and 4, the high-carbon solid edge 5 forming the nose 5 of the plowshare, the nose-point 9 and the lower blade 10 being sharpened, and the plowshare then submitted to the hardening operation. There is thus formed a plowshare having the solid hard steel nose 5 (forward of the dotted line 11, Figure 3) and the rearwardly extending laminated steel body, composed of the soft and tough center 2 and the opposite hard faces 3, 3.

It has been the practice heretofore to weld upon the inner side face of the nose portion of the plowshare a heel or so-called gunwale 12, the flange 13 of which has been only of a width sufficient to give a firm weld. It is a part of the present invention to extend the width of this welded flange portion 13 of the gunwale beyond the dotted line 11 of the front edge of the soft center 2 of the plowshare, to about the extent indicated by the dotted line 14 of Figure 3, so that it will reinforce the union between the hard steel nose and the front edge of the inner layer of the plowshare.

The terms "low-carbon" or "soft" steel, and "high-carbon" or "hard" steel, are used here-

in in a relative sense only. The so-called soft center 2 of the laminated metal plate may be of iron, or of any steel so low in carbon content as not to be hardened or only slightly hardened by heat treatment, so that it will constitute a tough supporting inner metal layer. The portions 3 and 5 of the plowshare will have a carbon content higher than that of the center layer 2, and consequently will be harder, being preferably hardened by heat treatment in the usual way.

10 No claim is made herein to the method of manufacture of plowshares described in the foregoing specification since the method is made the subject of a separate, divisional application for Letters Patent, filed by me on September 3rd, 1931, Serial No. 560,906.

I claim as my invention:

15 A plowshare comprising a solid nose and rearwardly projecting opposite wings formed of hard steel, a relatively soft metal integral filling projecting rearwardly from said nose between said wings, and a gunwale having a flange united to a side face of said nose and extending rearwardly beyond the line 25 of juncture of said nose with said soft metal filling.

20 In testimony whereof I have hereunto set my hand.
